UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER-LOOM.

1,372,083.

Specification of Letters Patent. Patented Mar. 22, 1921.

Application filed May 26, 1917. Serial No. 171,128.

To all whom it may concern:

Be it known that I, JONAS NORTHRUP, a citizen of the United States, residing at Hopedale, in the county of Worcester and 5 State of Massachusetts, have invented certain new and useful Improvements in Feeler-Looms; and I do hereby declare the following to be a full, clear, and exact description of the invention, such as will enable others skilled in the art to which it app- 10 pertains to make and use the same.

The present invention relates to an improvement in feeler looms, and more particularly the invention relates to an im- 15 provement in thread extracting devices for such looms.

When the filling in the active shuttle of a feeler loom is exhausted to a predetermined extent, the filling feeler mechanism 20 operates to initiate the weft replenishing operation, and thereupon the bobbin or filling carrier with a certain amount of filling still on it is ejected from the shuttle by the insertion of a filled bobbin therein. Inas- 25 much as the replenishing operation takes place before the filling in the active shuttle is completely exhausted, the filling thread will extend from the shed or selvage to the outgoing bobbin. It is customary to sever 30 this filling end relatively near the shuttle so that as the critically exhausted bobbin is forced out of the shuttle, it may draw this filling end after it through the shuttle eye. It sometimes happens, however, that 35 this filling end is caught between the shuttle and the front wall or the binder of the shuttle box, and consequently the bobbin drops to the bottom of its receptacle, leaving the filling end in the shuttle box and 40 extending through the shuttle eye. In such cases there is a liability of this filling end being drawn into the shed on the first pick of the shuttle after the replenishing operation. The presence of this filling end in the 45 shed is called a double pick and is a blemish in the cloth; and accordingly various devices have heretofore been proposed for eliminating this outgoing filling end, that is to say, for preventing its being drawn 50 into the shed and causing a double pick. Some of these proposed thread extracting devices have performed their function before the first evacuation of the shuttle box at the replenishing side of the loom after

the replenishing operation, and others have 55 performed their function after the first evacuation of the replenishing shuttle box by the shuttle after the replenishing op- eration.

The object of the present invention is to 60 improve the construction and organization of feeler loom thread extracting devices of the type which operate to extract the thread from the loom after the shuttle on its first pick away from the replenishing side of the 65 loom after replenishment has evacuated the shuttle box. To the accomplishment of this object and such other objects as shall hereinafter appear, the present invention consists in the improved thread extracting de- 70 vice described in the following specification and particularly pointed out in the ap- pended claims.

The preferred form in which it is con- 75 templated embodying the features of the present invention is illustrated in the accom- 80 panying drawings, in which Figure 1 is an end elevation of a portion of a feeler loom, showing the application of the im- proved thread extracting device of the pres- 85 ent invention thereto; Fig. 2 is a front ele- vation on an enlarged scale of parts of the thread extracting device; Fig. 3 is a section taken on the line 3—3 of Fig. 2; Fig. 4 is a view similar to Fig. 3, showing the parts 90 in a different position of operation; and Fig. 5 is a side elevation of the upper end of the thread hook actuating and resetting member.

The feeler loom to which the thread ex- 95 tracting device of the present invention is applied for the purpose of extracting the outgoing filling end from the shed or from the loom after the evacuation of the replenishing shuttle box by the shuttle on its first 100 pick after the weft replenishing operation, may be of any usual or preferred construc- 105 tion. The portion of the loom illustrated in the drawings comprises a frame 10, in the lower part of which is pivoted the rock shaft 11 for sustaining the lay swords 12 which support the lay 13, which is oscillated toward and from the breast beam 15. A change shaft 16 is journaled in brackets se- cured to the front of the breast beam, and extends transversely across the front of the loom, being connected at one end of the loom with the filling feeler mechanism and at

the other end of the loom through the hopper arm 17 with the weft replenishing mechanism. This change shaft 16 and the filling feeler mechanism constitute loom controlling devices. It will be observed that in the event of the application of the present invention to an automatic loom, the replenishing operations of which are initiated on the exhaustion or breakage of the filling, 5 the change shaft 16 would, in that case, be connected with the usual filling detector mechanism. But where a filling feeler mechanism is employed to control the operations of the weft replenishing mechanism, an operation of the latter is effected 10 when the filling feeler mechanism indicates that the filling in the active shuttle has been exhausted to a predetermined extent. Thereupon, an oscillation of the change shaft 16 results, on the following beat-up of the lay, in the insertion of a fresh supply of filling in the shuttle. The critically exhausted bobbin having been ejected from the shuttle it falls through the usual aperture 15 in the lay down into the bobbin receptacle or can 20.

If when the shuttle is boxed at the replenishing side of the loom the outgoing filling end, that is to say, that portion of the 20 filling which extends from the selvage to the outgoing bobbin, is not caught between the shuttle and the binder or front wall of the shuttle box, the descending bobbin will pull it through the shuttle eye clear of the 25 loom, the usual thread parter having first operated to sever it relatively near the shuttle, and therefore no double pick can result. If, however, this portion of the outgoing filling end should be caught between 30 the shuttle and the binder or the front wall of the shuttle box, then on the first pick of the shuttle away from the replenishing side of the loom this filling end will be drawn into the loom toward the cloth and, most frequently, into the shed and thereby cause a 35 double pick. The improved thread extracting device of the present invention operates after the outgoing filling end has been drawn into the loom or into the shed by the 40 shuttle, to pull it therefrom.

The improved thread extracting device is shown in the illustration of its preferred embodiment as comprising a thread hook 22 which is adapted, at the proper times, to 45 engage an outgoing filling end which has been drawn into the shed and extract it therefrom before the warp threads close together upon it. This thread hook 22 has on its upper extremity a thread hook proper or 50 filling engaging part 23. During the normal or regular weaving operation of the loom, the thread hook 22 is arranged substantially vertical alongside the filling replenishing end of the loom. The lower end 55 24 of the thread hook serves as a pivot pin

or shaft upon which the thread hook is mounted. The shaft portion 24 of the thread hook is journaled in bearings 25 and 26 formed on the upper end of a bracket plate 27 secured to the side of the loom 70 frame.

The thread hook 22 is adapted to be oscillated in its bearings on the first backward beat of the lay after replenishment, and for this purpose the thread extracting device is 75 provided with a thread hook actuator 29 adjustably secured to the upper end of a rod 30 which is pivotally connected with the outer end of an arm 31 secured to the rock shaft 11. A spring 32, connected with the 80 arm 31 and with the rod 30, acts normally to force the actuator 29 toward the front of the loom, this yielding connection between the arm 31 and the rod 30 being provided so that the actuator 29 may be deflected rearwardly at the proper time, in order to actuate the thread hook. For the purpose of actuating the thread hook to cause it to swing outwardly from the loom, the actuator 29 is provided with a cam surface 34 which is adapted, on the first backward beat of the lay after replenishment, to 85 come into engagement with a cam projection or lug 35 projecting from a hub 36 rigidly secured to the shaft portion 24 of the thread 90 hook. This lug 35, while the thread hook is in normal position, presses against the upper end 37 of the bracket 27, as shown in Fig. 3. The cam surface 34 of the actuator 29 is prevented from engaging with the lug 35 during regular weaving, and for this purpose the actuator 29 is provided with a laterally flaring part 38 in the under side of which is a groove 39 which is normally in alignment with a downwardly projecting 100 guide finger 40 of an actuator controller member 41 pivoted at 42 on the bracket 27. During regular weaving, the controller 41 is held in the position shown in Fig. 1, so that as the actuator 29 is caused to rise, by 105 reason of the connections between it and the rock shaft 11, on the backward beat of the lay, the groove 39 engages the guide finger 40 and the actuator is thereby caused to rise 110 inoperatively, so that its cam surface 34 passes the lug 35 without engaging it. The actuator controller 41 is adapted to be moved at the proper time to permit the actuator 29 to be deflected so that its cam 115 surface 34 may come into engagement with the lug 35 to actuate the thread hook, and for this purpose the controller 41 is connected with an arm 43, secured to the change shaft 16 and extending rearwardly therefrom, by means of a rod 44 which is pivotally connected at its lower end with the controller and at its upper end is loosely received in a hole in a boss 45 secured to the outer end of the arm 43. A spring 46, one 120 end of which is secured to the rod 44 and 125 130

the other end of which is secured to the boss 45, permits relative movement between the arm 43 and the rod 44, for a purpose to be presently described. The oscillatory movements of the pivoted actuator controller 41 are limited by a stop lug 48, which projects into a notch 49 in the controller.

The thread hook actuator 29 operates on the first return beat of the lay after replenishment to cause the thread hook to move outwardly from the loom; and on the next succeeding backward beat of the lay the actuator 29 operates to return the thread hook to its normal or inoperative position. For this latter purpose the actuator is provided with two cam projections 50 and 51, which are arranged to successively engage, as the actuator rises, with corresponding cam lugs 52 and 53 respectively, secured to the hub 36.

The actuator 29 does not move the thread hook to the full extent of its outward movement from the loom, nor does it move the thread hook to the full extent of its return or resetting movement toward the loom. The actuator 29 simply initiates the outward movement of the thread hook and the resetting movement thereof. The outward movement of the thread hook 23 is completed by a spring 54, and the return movement of the thread hook is completed by the same spring. This spring 54 is secured at its lower end to the bracket 27, and at its upper end to a curved piece 55 which is pivotally connected at its upper end with an arm 56 projecting outwardly from the hub 36. This arm 36 is so arranged that when the thread hook is in normal position, the line of pull exerted upon the pivotal connection 57 between the arm 56 and the piece 55 is to the rear of the shaft portion 24 of the thread hook, as shown in Fig. 3, and when the hook has been moved outwardly from the loom, the pull of the spring is on the front side of the shaft portion 24, as shown in Fig. 4. A stand 59 having a notched end 60 is provided for the purpose of limiting the downward movement of the thread hook.

The operation of the thread extracting device is as follows: While the loom is running normally, that is to say, during regular weaving, the thread hook 22 occupies its position alongside the loom frame, as shown in Fig. 1, and the thread hook actuator 29 moves constantly upwardly and downwardly, its cam surface 34 being held from engagement with the lug 35 by the guide finger 40 of the controller 41. But when the filling feeler mechanism indicates that the filling in the active shuttle has been exhausted to a predetermined extent, the change shaft 16 is turned in a counter-clockwise direction, and the arm 43 is raised. The turning of the change shaft 16

and the consequent raising of the arm 43 take place on the backward beat of the lay, and the timing of the movements of the various parts is such that before the arm 43 can actuate the controller 41 and swing the 70 guide finger 40 to the left, the actuator 29 has risen, so that the groove 39 engages with the guide finger 40. As the arm 43 rises, the loose connection between it and the rod 44 permits it to rise without imparting any 75 motion to the rod 44, the controller 41, therefore, remains in normal position, and the cam surface 34 on the actuator 29 is kept from engagement with the lug 35. By the time the lay has reached its rear center, 80 the shuttle has been picked to the replenishing side of the loom, and then the lay beats forward on the replenishing beat-up. As the lay beats forward, the actuator 29 is disengaged from the guide finger 40, and thereupon the spring 46 acts to lift the rod 44 and oscillate the controller 41, swinging the 85 guide finger 40 to the left. It will be observed at this point that the tension of the spring 46 is so adjusted that during regular weaving it acts as an expansion spring to force the rod 44 downwardly; but when the arm 43 has been raised, the spring 46 acts as a contraction spring to pull the rod 44 upwardly. The position of the actuator 90 29 and its controller at this time is indicated in dot and dash lines in Fig. 2. The replenishing operation takes place while the lay is substantially on its front center, and upon the completion of the replenishing 95 operation the lay beats backward. Coincident with the backward movement of the lay the actuator 29 rises and the cam surface 62 formed on the side of the projection 38 comes into engagement with the corresponding cam surface 63 formed on the inner side of the guide finger, so that as the actuator 29 continues to rise, it is deflected to the right into alignment with the lug 35, as shown in dot and dash lines in Fig. 2, 100 105 the pivotal connection between the rod 30 and the arm 31 permitting this deflecting movement of the actuator. Then as the actuator completes its rising movements, its cam surface 34 strikes the lug 35 and oscillates the shaft 24 until the outer end of the arm 56 is swung to the front of the shaft 24, and thereupon the spring 54 acts to complete the outward and downward movement of the thread hook. The movements 110 115 of the various parts have been described as taking place during the backward beat of the lay after the replenishing operation. It will be observed, however, that the thread hook actuation is not initiated until the 120 125 lay is substantially on its rear center. The actuation of the thread hook is so timed that the shuttle has had opportunity to evacuate the replenishing shuttle box before the thread hook moves outwardly from the 130

loom. Of course if no outgoing filling end was caught between the shuttle and the binder or front wall of the shuttle box, the thread hook moved outwardly without engaging the filling end, because the latter had been pulled down through the shuttle eye by the bobbin in the usual manner. But if the outgoing filling end was caught in the shuttle box, then the outward movement of the thread hook caused it to be engaged and pulled out of the shed and from the loom.

While the lay was beating backward after replenishment, the change shaft 16 and the arm 43 were returning to normal position, but inasmuch as during these movements the controller 41 was held locked by the actuator 29, in the position shown in dot and dash lines in Fig. 2, the arm 43 moved downwardly relatively to the rod 44 without causing an actuation of the latter. The lay now beats forward, and the actuator 29 descends, the spring 32 forcing it outwardly, so that by the time the cam face 62 passes below the cam face 63 on the guide finger 40, the actuator is restored to its normal position with its groove 39 in alignment with the position normally occupied by the guide finger. The disengagement of the cam face 62 from the cam face 63 permits the spring 46, now under compression, to force the rod 44 downwardly, thereby oscillating the controller 41 and restoring the guide finger 40 to its normal position. The actuator 29 and its controller 41 are now in normal position, so that on the next backward beat of the lay, that is to say, the second backward beat of the lay after replenishment, the groove 39 again engages the guide finger 40 as the actuator 29 rises. As the actuator 29 rises on this second backward beat of the lay after replenishment, the cam projection 50 first comes into engagement with its corresponding cam lug 52 secured to the shaft 24, and causes the shaft to be oscillated to begin its return or resetting movement. Then as the actuator continues to rise, the cam projection 51 comes into engagement with its corresponding cam lug 53, and the shaft 24 is thereby oscillated far enough so that the spring 54 can complete the resetting of the thread hook.

Having thus described the invention, what is claimed is:—

55 1. A thread extracting device for looms having, in combination, a thread hook arranged to swing outwardly from the loom, means for actuating the thread hook on the first backward beat of the lay after replenishment, and means for resetting the thread hook on the second backward beat of the lay after replenishment.

60 2. A thread extracting device for looms having, in combination, a thread hook, a shaft for supporting the thread hook, pro-

jections on the shaft, an actuator connected with the lay rock shaft having parts normally disconnected from but adapted on weft replenishment to coöperate with the projections to actuate the thread hook and to 70 reset it, and a controller connected with the change shaft of the loom for controlling the action of the actuator.

3. A thread extracting device for looms having, in combination, a thread hook, an oscillatory shaft upon which the thread hook is mounted, and means connected with the lay rock shaft to actuate the oscillatory shaft to impart a thread extracting movement to the thread hook on one backward 75 beat of the lay and to impart a resetting movement to the thread hook on the next backward beat of the lay.

4. A thread extracting device for looms having, in combination, a thread hook, a shaft on which the thread hook is mounted, an arm projecting outwardly from the shaft, a spring connected therewith, and means for actuating the shaft to shift the position of the arm so that the spring may 80 complete the action of moving the thread hook.

5. A thread extracting device for looms having, in combination, a thread hook mounted to swing outwardly away from the loom, a spring connected therewith, and means connected with the lay rock shaft for initiating the outward swing of the thread hook and the resetting movement of the thread hook, said spring acting to complete the outward swing of the thread hook and the resetting thereof.

6. A thread extracting device for looms having, in combination, a pivotally mounted thread hook, an actuator therefor connected with the lay rock shaft and arranged to have a constant reciprocatory motion during regular weaving, and means to prevent the actuation of the thread hook by the actuator during regular weaving and to 105 permit the actuation of the thread hook by the actuator on the first backward beat of the lay following replenishment.

7. A thread extracting device for looms having, in combination, a thread hook, an oscillatory shaft on which the thread hook is mounted, cam projections on the shaft, an actuator for engaging the cam projections to initiate the thread extracting operation of the thread hook and the resetting thereof, and a spring connected with the shaft to complete the thread extracting operation and the resetting movement of the thread hook.

8. A thread extracting device having, in 125 combination, a thread hook, a shaft on which the thread hook is mounted, cam projections on the shaft, a thread hook actuator having parts coöperating with the cam projections on the shaft to actuate the thread 130

hook, connections between the actuator and the lay rock shaft whereby the actuator is caused to have a constant reciprocatory movement, a controller for preventing the actuation of the thread hook during regular weaving and for permitting the actuation thereof on weft replenishment, and con-

nections between the controller and the change shaft permitting the thread hook to be actuated on the first backward beat of 10 the lay after replenishment and to be reset on the second backward beat of the lay after replenishment.

JONAS NORTHROP.
